United States Patent

Des. 241,228

Patented Aug. 31, 1976

241,228

PACKAGING CONTAINER FOR FOOD OR THE LIKE

Stanley W. Boduch, Ludlow, Mass., assignor to Dart
Industries Inc., Los Angeles, Calif.

Filed Nov. 7, 1974, Ser. No. 522,082

Term of patent 14 years

Int. Cl. D9—03

U.S. Cl. D9—220

FIG. 1 is a perspective view of a packaging container for food or the like showing my new design;

FIG. 2 is a perspective view thereof in an inverted position;

FIG. 3 is a perspective view showing another embodiment of my new design;

FIG. 4 is a perspective view thereof in an inverted position; and

FIG. 5 is an enlarged fragmentary view of the upper portion of either embodiment.

I claim:

The ornamental design for a packaging container for food or the like, substantially as shown and described.
